NOVELTY GLOVE

Robert Stanton, 140 Geary St., San Francisco, Calif.

Filed July 21, 1960, Ser. No. 61,464

Term of patent 14 years

(Cl. D3—11)

FIG. 1.

FIG. 2.

Fig. 1 is a rear view of a novelty glove showing my new design; and

Fig. 2 is a rear perspective view thereof as it appears with the thumb inserted between the index and middle finger to show the composite design.

The front or palm side of the glove is conventionally plain.

I claim:

The ornamental design for a novelty glove, as shown and described.
